UNITED STATES PATENT OFFICE.

ARTHUR T. GLEW, OF GERMANTOWN, OHIO.

DESIGN FOR AN ARTIFICIAL INCISOR TOOTH.

SPECIFICATION forming part of Design No. 32,478, dated April 10, 1900.

Application filed January 29, 1900. Serial No. 3,239. Term of patent 14 years.

To all whom it may concern:

Be it known that I, ARTHUR T. GLEW, a citizen of the United States, residing at Germantown, in the county of Montgomery and State of Ohio, have invented and produced a new and original Design for an Artificial Incisor Tooth, of which the following is a specification, reference being had to the accompanying drawings, forming part thereof.

Figure 1 is a side view of an upper incisor tooth, showing my new design. Fig. 2 is a front view of the tooth. Fig. 3 is an end view of the tooth.

The leading feature of my design is the broad straight smooth groove 1, extending across the base of the incisor tooth, leaving rear and front projections 2 and 3, whose inner sides are straight and parallel, and thus

equidistant from one side of the tooth to the other, as shown. A minor feature is the form 20 of the said projections 2 3, the rear one, 2, having a more acute angle and less length than the outer one, 3. The upper or root portion of the tooth is reduced and wedge-shaped and curved forward, so that it is practically in line 25 with the said projection 3.

Having described my invention, what I claim, and desire to secure by Letters Patent, is—

The design for an artificial upper incisor 30 tooth, substantially as shown and described.

ARTHUR T. GLEW.
